Inventor
Richard Max Eaton.
By his Attorney
Mark C. Fischer.

UNITED STATES PATENT OFFICE.

RICHARD MAX EATON, OF NIAGARA FALLS, NEW YORK.

FLASH LIGHT.

Application filed March 18, 1920. Serial No. 366,892.

To all whom it may concern:

Be it known that I, RICHARD MAX EATON, a citizen of the United States, residing at Niagara Falls, in the county of Niagara and State of New York, have invented certain new and useful Improvements in Flash Lights, of which the following is a full, clear, and exact description.

The principal object of this invention is to provide a switch, specially adapted for use in connection with portable electric search lights, by the operation of which the lamp may be caused to glow temporarily producing a single flash, extended in duration by holding the button depressed, or by shifting the position of the button, to cause a continuous emission of light.

A further object is to provide an effective guard for the single button used, protecting it against inadvertent displacement, means also being provided for maintaining the button in either of its adjusted positions.

These and other objects, such as simplicity of structure, assemblage and operation are attained by the novel construction, combination and arrangement of parts hereinafter described and shown in the accompanying drawings, forming a material part of this specification, and in which:—

30 Figure 1, is a top side elevational view of a search light made in accordance with the invention.

Figure 2 is a longitudinal sectional view taken on line 2—2 of Fig. 1.

35 Figure 3, is an enlarged fragmentary sectional view taken through the switch, contact and support.

Referring to the drawings in detail, the numeral 10 designates the cylindrical hollow body of a conventional type of search light or electric torch, the same being made of nonconducting material and adapted to be grasped by the hand.

40 Engaged by the rivet 13' is a metallic strip conductor 30 secured at its inner end by a similar rivet 31.

Another strip conductor 35 is arranged in register with the strip 30, its free front end 35' extending into the head 11 so as to make 50 contact with the exterior of the reflector 18.

The strip 35 is firmly held in engagement to the interior of the body 10 by another tubular rivet 36, immediately rearward of which the strip is sheared to produce a 55 tongue 38 bent to extend outward and upward through an opening 39 formed in the

wall of the body 10, the extreme end of the tongue resting on the outer head of the rivet 36.

The end 40 of the strip 35 is also turned outwardly and upwardly, extending through another opening 41 in the wall of the body, as can best be seen in Fig. 3.

A thin metallic casing or housing 44 is provided with flanged feet extensions 45 and 45', held securely to the exterior of the body by the rivets 31 and 31', and formed longitudinally in the casing 44 is a slot 46, adjacent to the rear end of which is a raised abutment or guard 47.

70 Slidably engaged in the slot 46 is a stem 48 having an extending operative button or head 50, the inner end of the stem 48 being riveted or otherwise firmly secured in a plate 51 having an upturned angular end 52 75 engageable within the recess formed in its abutment 47, as shown in Fig. 2, thereby locking the stem, button and plate.

The outer end of the plate 51, which is made of spring material of conducting nature, is turned reentrantly, forming a bend 53, from which extends a spring contact 54, disposed below the plate 51 and terminating in a curved strip 55, slideable on the exterior of the non-conducting body 10 and adapted 85 to act as a detent when over the opening 39, holding the parts in a forward position.

In operation, when no light is required, the button 50 is moved to the rear until the end or detent 52 engages in the recess of the 90 abutment 47 at which time the abutment, extending as it does flush or level with the top of the button, acts as a protecting guard against inadvertent contact or pressure on the button.

95 If a flash or temporary light is desired, the button 50 is manually depressed, causing the outer end of the plate 51 to make contact with the element 40 of the conductor strip 35, thus conveying current from the battery 100 through the ferrule, cap and strip 30 to the end 40 and thence through strip 35 reflector 18, socket and stem to the bulb 20, the inner contact of the stem being in electrical contact with the other pole of the battery.

105 Thus during the depression of the button a light is obtained of a temporary nature; if however, a continuous light is required the button 50 is depressed and moved towards the head, causing the spring contact 54 to 110 engage the tongue 38 and form a circuit in the manner before described, the device mak-

ing direct and positive metallic circuit contacts throughout.

Having thus described my invention and set forth its purpose, manner of construction and application, what I claim as new and desire to secure by Letters Patent, is:—

1. A switch comprising a support, a casing thereon, said casing having an elongated slot, a hollow abutment on said casing adjacent one end of the slot, a conductor in circuit with said casing, a second conductor engaged to said support below said casing, a tongue and a spaced terminal formed with said second conductor extending through said support, a spring contact slideable in said housing, a button for operating said contact, said button having a stem extending through the mentioned slot, a detent formed with said contact engageable in said abutment and a spring detent formed with said contact engageable in the opening through which said tongue extends when said contact is in circuit with said tongue, said contact being engageable with said terminal upon depression of said button when the contact is at the opposite end of the slot.
2. A switch comprising a support, a slotted casing thereon, a hollow abutment on said casing adjacent one end of the slot a pair of conductors secured below said support, one of said conductors being in electrical engagement with said casing and the other insulated therefrom, a tongue and terminal formed with said insulated conductor extending into said casing, a movable contact in said casing adapted to engage either the tongue or terminal means engageable with the hollow abutment of said casing for normally maintaining said contact in its inoperative position and a single operating means for said contact accessible from the exterior of said casing.

3. A switch comprising a support, a slotted casing thereon, a hollow abutment on said casing adjacent one end of the slot, a pair of conductors secured below said support, one of said conductors being in electrical engagement with said casing and the other insulated therefrom, a tongue and terminal formed with said insulated conductor extending into said casing, a movable contact in said casing adapted to engage either the tongue or terminal means engageable with the hollow abutment of said casing for nor-

mally maintaining said contact in its inoperative position a single button for operating said contact into either of its positions and for causing contact with said terminal when at one end of the slot in said casing.

4. A switch comprising a support, a slotted casing thereon, a hollow abutment on said casing adjacent one end of the slot, a pair of conductors secured below said support, one of said conductors being in electrical engagement with said casing and the other insulated therefrom, a tongue and terminal formed with said insulated conductor extending into said casing, a contact engageable upon depression with said terminal when at one end of said casing and engageable with said tongue without depression at the other end, and a single operating means for said tongue.

5. A switch comprising a support, a slotted casing thereon, a hollow abutment on said casing adjacent one end of the slot, a pair of conductors secured below said support, one of said conductors being in electrical engagement with said casing and the other insulated therefrom, a tongue and terminal formed with said insulated conductor extending into said casing, a contact engageable upon depression with said terminal when at one end of said casing and engageable with said tongue without depression at the other end, a single means for depressing and shifting said contact, and means for holding said contact in its forward position.

6. A switch comprising a support, a slotted casing thereon, a hollow abutment on said casing adjacent one end of the slot, a pair of conductors secured below said support, one of said conductors being in electrical engagement with said casing and the other insulated therefrom, said insulated conductor having two points of contact, a sliding and compressible contact element movable in said casing, a button controlling said contact element, a guard for said button and means for retaining said movable contact element in its forward position.

This specification signed and witnessed this 11th day of March, 1920.

RICHARD MAX EATON.
